UNITED STATES PATENT OFFICE

2,435,738

FASTENER INSERTING TOOL

Henry H. Crafton, Baden, Pa., assignor to H. H. Robertson Company, Pittsburgh, Pa., a corporation of Pennsylvania

Application September 9, 1944, Serial No. 553,317

7 Claims. (Cl. 29—200)

1

This invention relates to a tool particularly adapted for use for widening an open cell of a corrugated metallic building sheet and for inserting a fastening member therein.

The invention has for an object to provide a novel and improved tool of the character specified adapted for use in the erection of a roof or floor structure embodying a metal building sheet having a corrugated upper surface and a plurality of insulating sheets or the like erected on the upper surface thereof, the present tool being used to facilitate the insertions of fastening members to the corrugations of the metal building sheet for securing the insulating sheets thereto.

In the drawings illustrating the preferred embodiment of the invention, Fig. 1 is a perspective view of a portion of a floor or roof structure embodying a fastening clip inserted by the present tool; Figs. 2 and 3 are detail views in end and front elevations respectively of the fastening clip; Fig. 4 is a plan view in cross section taken on the line 4—4 of Fig. 5 of a tool embodying the present invention shown in its retracted position; Fig. 5 is a side elevation of the tool shown in Fig. 4 with one side plate removed and showing a fastening clip in position to be inserted in a corrugated building sheet; Fig. 6 is a plan view detail of a portion of the tool shown in Fig. 5 to be hereinafter referred to; Figs. 7 and 8 are views similar to Figs. 4 and 5, respectively, showing the tool in its extended position inserting a fastening clip; Fig. 9 is a cross sectional view taken on the line 9—9 of Fig. 5; and Figs. 10 and 11 are views in cross section taken on the lines 10—10 and 11—11 respectively of Fig. 8.

In general the present invention contemplates a tool for use in inserting a fastening clip between the side walls of the corrugations of a corrugated metal sheet. The latter may comprise an element in a built-up floor or roof deck, wherein the load supporting members of the roof or floor deck comprise corrugated metal sheets, mounted in contiguous relation and wherein slabs or sheets of insulating or other covering material are affixed to the upper surfaces of the corrugated sheets by novel and superior fastening means, including the aforesaid fastening clip. The present tool may be used with advantage to insert fastening clips into the corrugations of the metal sheets to thereby facilitate the fastening to the metal sheets of a perforate reinforcing and fastening strip, which is interposed between the clip member and the metal sheets and is extended over the upper surfaces of two adjacent insulat-

2

ing slabs, to be bonded thereto by the usual asphaltic waterproofing which may be applied over the upper surfaces of the insulation. In practice either additional finishing material or waterproofing felt may be applied over the perforate metal strips and over the insulation to complete the roof or floor deck. The metal clip and perforate strips serve to firmly anchor the insulation to the corrugated metal base members.

Referring now to the drawings, 10 represents a metal floor or roof deck which may and preferably will comprise the corrugated metal building structure forming the subject matter of the United States patent to Young, No. 1,867,433, July 12, 1932, to which reference may be made. The insulating sheets 14 may comprise any usual or preferred form of preformed insulating sheet material and are erected in contiguous relation upon the upper surfaces of the roof or floor deck 10 and preferably extend across the corrugations 15 therein as illustrated in Fig. 1. In the construction of the illustrated roof, fastening clips, indicated generally at 16, may be secured in the open cells 18 of the corrugated metal deck adjacent the edge of an insulating sheet. As best shown in Figs. 2 and 3, each fastening clip 16 comprises a sheet metal member having a lower or deck engaging portion 20 bent in a triangular shape as viewed in side elevation, see Fig. 3, to fit within 25 a widened portion of a cell, and, an upper portion comprising upwardly extended portions 24, 26 arranged face to face and being laterally extended, as indicated at 28, 30, beyond the side walls 32, 34 of the open cell 18 and on top of 30 a widened portion of a cell, and, an upper portion comprising upwardly extended portions 24, 26 arranged face to face and being laterally extended, as indicated at 28, 30, beyond the side walls 32, 34 of the open cell 18 and on top of 35 adjacent and oppositely extending corrugations.

As illustrated in Fig. 9 the side walls 32, 34, of the cell 18 are upwardly diverging so that the cell is wider at the top than at the bottom. By means of the present tool the fastening clip is 40 anchored between the upwardly diverging side walls 32, 34 by widening the cell and holding the cell open below the clip, permitting the latter to drop down to the position illustrated, and, upon being released the side walls tend to spring 45 back to their original shape to grip the base portion 22 of the clip tightly and firmly in position between the cell walls.

Referring now to Figs. 4 to 11, the present tool 50 comprises a housing including a pair of side frame members 40, 42 connected together by bolts 44, and a base member 46 attached to the side frames by bolts 48. A pair of wedge operated blocks 50, 52 slidingly supported for lateral movement in guideways formed in the side frames 40, 55 42 are arranged to be extended and retracted in

said guideways by a longitudinally movable wedge member 54 slidably supported between the side frames. As best shown in Fig. 9, the wedge operated widening blocks 50, 52 are preferably connected to the wedge member 54 by co-operating tongue and groove connections 56, 58, respectively, Figs. 4 and 7, to effect outward movement of the blocks when the wedge member is moved forward, and inward movement thereof when the wedge member is moved rearwardly. The wedge member 54 is guided longitudinally in the tool by the provision of a tongue 60 formed on the underside thereof which cooperates with a groove 62 formed in the base member 46 and a groove 64 formed between contiguous portions of the side frames 40, 42.

The tool housing is relatively narrow and elongated in form and is designed to fit within a channel or open cell 18 of the corrugated deck 10, as illustrated. The longitudinally movable wedge member 54 is arranged to be reciprocated to effect the widening operation by a lever 66 pivotally mounted on a stud 68 supported between the side frames and which is connected to the wedge member by links 70, 72 as clearly shown in Figs. 4 and 5. The lever 66 is provided with an elongated handle 74 for manually operating the tool.

From the description thus far it will be observed that when the tool is placed within an open cell 18 and the handle 74 is pulled rearwardly the wedge member 54 is moved forward to force the wedge blocks 50, 52 against the sidewalls 32, 34 to effect widening of a portion of the open cell 18 and when the handle is rocked forwardly the wedge blocks are retracted to release the pressure against the side walls. As above stated provision is made for supporting a fastening clip 16 in the tool in a position to permit the clip to be inserted into the widened space formed by the tool, and, as herein shown, the tool is arranged to receive a fastening clip between arms 76, 78 of an angularly disposed clip inserting member 80 slidably mounted in the tool in tongue and groove connections 82. The clip inserting member supports the clip in a vertical position as shown in Figs. 5 and 9, and is arranged to be urged downwardly to insert the clip in the widened portion of the channel 18 by springs 84 supported in the side frames 40, 42. As herein shown, one end of each spring 84 is supported in a threaded opening 86 provided with an adjusting screw 88, and the other end bears against a lug 90 slidably received in an opening provided in a block 92 secured to the tool. The lug 90 is connected to the clip inserting member 80 by a shouldered stud 94.

In order to prevent the fastening clip from being urged downwardly into the channel 18 before the widening operation has commenced, an extension 96 from the under side of the inserting member 80 is arranged to engage a stop 98 carried in the longitudinally movable wedge member 54, as shown in Fig. 5. In practice the operator slides the inserting member upwardly against the action of the springs 84 by means of a finger grip 100 and then places a fastening clip between the arms 76, 78 thereof. The inserting member is then released to come to rest against the stop member 98. Thereafter, when the tool is operated to move the wedge 54 forwardly to effect widening of the open cell 18, the stop member carried by the wedge is moved forwardly as shown in Fig. 8 to permit the springs 84 to push the inserting member downwardly and place the clip between the sides of the widened portion of the cell. On the return stroke, the stop member

98 again engages the extension 96 to lift the inserting member 80 up to its original position. It will be observed that on the return stroke the pressure of the wedge blocks 50, 52 is released to permit the side walls 32, 34 to grip the fastening clip 16 before the stop member 98 effects raising of the inserting member thus preventing displacement of the clip from the cell during retraction of the inserting member.

10 In order to prevent displacement of the tool in the channel 18 during the widening operation, a second pair of laterally movable wedge operated blocks 102, 104 are provided which are arranged to engage the upper edges of the side walls 32, 34 as shown in Fig. 11. The blocks 102, 104 are connected to an upper wedge shaped portion 106 of the longitudinally movable wedge 54 and are operated simultaneously with the cell widening blocks 52, 53 to exert a grip between opposed edges of the cell during the widening operation to assure centering of the tool in the channel and to prevent tipping or longitudinal displacement of the tool therein during the widening operation.

From the above description, it will be observed that in operation, the tool provided with a fastening clip 16 is placed in an open cell 18 and moved forwardly to present the clip adjacent the edge of a sheet of insulation 14 or other sheet to be attached to the corrugated metal section, as shown in Fig. 5. The handle 74 is then rocked backwardly to effect widening of the cell, as above described. It will be observed that the widening or expanding blocks 50, 52 are disposed in the lower portion of the cell 18 to effect widening of the upwardly diverging side walls 32, 34 at a point substantially medially thereof, and that the portions of the side walls extending above the widening blocks are caused to assume a substantially vertical and parallel position at which time the clip drops down into the cell. As illustrated in Figs. 8 and 10, the clip is permitted to drop down into the cell until it rests against the top surface of the wedge blocks 50, 52 and, upon release of the expanding pressure, the base portion 22 of the clip is firmly gripped between the side walls 32, 34 of the cell as the walls tend to return to their original position. Thereafter, the tool is pulled out from under the clip and removed and, in the erection of the roof structure a second sheet of insulation is erected in contiguous relation to the first sheet so that the upper portions of the clip extend between adjacent sheets. In practice, and, as herein illustrated, the fastening clips 16 may be provided with cooperating wire mesh pieces 108 bent around the underside of the laterally extended portions 28, 30 of the clip and positioned to extend over the upper surfaces of adjacent insulating sheets. A protective covering embodying a waterproofing adhesive 110 and roofing paper 112 may then be applied to the upper surfaces of the insulating sheets 14, the wire mesh becoming embedded in the waterproofing adhesive and cooperating with the fastening clip to secure the sheets to the corrugated metal roof deck.

While the preferred embodiment of the invention has been herein illustrated and described, it will be understood that the invention may be embodied in other forms within the scope of the following claims.

Having thus described the invention, what is claimed is:

1. A tool for inserting a fastening member in a corrugated metal building sheet comprising an elongated housing adapted to be placed within

an open cell of the corrugated metal sheet, means carried by said housing for supporting a fastening member, a pair of laterally movable blocks supported in said housing, means for spreading said blocks apart into engagement with opposed side walls of said open cell to effect widening of the latter to permit reception of said fastening member, said fastener supporting means having provision for automatically depositing a fastener into the widened portion of said cell.

2. A tool for inserting a fastening member in a corrugated metal building sheet comprising a housing adapted to be placed within and moved longitudinally of an open cell of the corrugated metal sheet, a pair of laterally movable blocks mounted in said housing, means for moving said blocks into engagement with opposed side walls of said open cell to effect widening of the latter for the reception of a fastening member, and a second pair of laterally movable blocks spaced from said first pair and arranged to bear against opposed side walls of said cell for preventing displacement of the housing in the cell during operation of the tool, and means for automatically depositing a fastener in the widened portion of the corrugation.

3. A tool for inserting a fastening member in a corrugated metal building sheet comprising a housing adapted to be placed within and moved longitudinally of an open cell of the corrugated metal sheet, a pair of laterally movable blocks mounted in said housing, means for moving said blocks into engagement with opposed side walls of said open cell to effect widening of the latter for the reception of a fastening member, means carried by the housing operative to engage the side walls of said cell for preventing displacement of the housing in the cell during operation of the tool, and means for automatically depositing a fastener in the widened portion of the cell.

4. A tool for inserting a fastening member in a corrugated metal building sheet comprising a housing adapted to be placed within an open cell of the corrugated metal sheet, yieldingly mounted means for holding a fastening member arranged to urge the same downwardly into the open cell, a pair of pressure applying members mounted in said housing for engaging opposed side walls of said open cell to widen the latter and means for actuating said pressure applying members to effect widening of said cell to permit said fastening member to be inserted therein by said yieldingly mounted holding means.

5. A tool as claimed in claim 4 having a stop member carried by said actuating means arranged to retain said yieldingly mounted holding means in an upward position when said actuating means is retracted and to release said holding means upon movement of said actuating means to effect the widening operation.

6. A tool for inserting a fastening member between the upwardly diverging side walls of one of the corrugations of a corrugated metal sheet comprising a housing adapted to be placed between the side walls of said corrugation, a yieldingly mounted slide member carried by said housing and arranged to hold a fastening member in operative position to be received between said side walls, a pair of laterally movable wedge blocks mounted in said housing, a longitudinally movable wedge arranged to move said blocks against opposed side walls to effect widening of a portion of said corrugation to permit said fastening member to drop into said widened portion, said fastening member becoming anchored between said side walls upon release of said widening pressure and removal of the tool.

7. A tool for inserting a fastening clip within a corrugation of a corrugated metal sheet, comprising a body portion adapted to fit into the corrugation, an operating member, means actuated upon movement of the operating member in one direction for engaging the walls of and effecting widening of the corrugation and for disengaging said walls when the operating member is retracted and means for depositing a clip in said widened portion, whereby to enable the clip to be clamped between the walls of the corrugation when the operating member is retracted.
